UNITED STATES PATENT OFFICE

LAWRENCE E. YAGGI, OF EAST CLEVELAND, OHIO.

DEVICE FOR PRACTICING GOLF STROKES

Application filed March 18, 1930. Serial No. 436,719.

This invention relates to devices for practicing golf strokes, and has for its main object to provide a device which is especially adapted for the practicing of golf strokes 5 within doors.

Another object of the invention is to provide a device for practicing golf strokes, which is simple in construction, inexpensive to manufacture, convenient to carry, and 10 when placed upon the floor will protect same from the blows of the golf club and remain stationary even under repeated action of the blows.

For a clear understanding of the invention, 15 reference will be had to the accompanying drawing illustrating the same, and the novel features thereof will be particularly pointed out in the appended claims.

In the several views of the drawing, similar 20 characters of reference are used to designate corresponding parts.

Figure 1 is a side elevation of a device for 25 practicing golf strokes constructed in accordance with my invention,

Fig. 2 is an end view thereof,

Fig. 3 is a plan view,

Fig. 4 is an elevation of the target,

Fig. 5 is an edge view thereof, a certain 30 part being broken away to better show the construction,

Fig. 6 is a sectional view taken on line 6—6 of Fig. 7,

Fig. 7 is an underside view of Fig. 6, and

Figs. 8 and 9 are views corresponding to 35 Figs. 6 and 7 illustrating a modification.

Referring to the drawing, 1 represents a mat or base preferably of rubber of rectangular form having a raised diamond shaped center 2 with forward and rear end points 40 3 and 4 and strips 5 extending longitudinally of the mat or base. The mat or base is provided with a transversely extending rectangular slot 6, and extending longitudinally from said recess at each side thereof and in 45 opposite directions are recesses 7 and 8 formed in the underside 9 of said mat or base.

Supported in the transverse slot 6 is a target 10, which is constructed of flexible sheet 50 rubber and consists of a head 11 in the form

of a circle on a neck 12. Said neck is split vertically from its lower end at 13, and embedded in each half thereof indicated by 14 and 15 is a strip of tin or other suitable metal as indicated at 16. The lower portion of the neck 12 is inserted through the transverse slot 6 of the mat or base 1 and the halves 14 and 15 of said neck are bent in opposite directions and forced within the recesses 7 and 8. The recesses 7 and 8 are made of suitable size so that the halves 14 and 15 of the neck 12 fit snugly into said recesses, and the strips of tin 16 in said halves also tend to hold said halves in set positions in said recesses.

In the modification in Figs. 8 and 9, the 55 base 17 is provided with a slot 18 for receiving the neck 19 of the target 20, and a circular button 21 at the base of said neck is adapted to fit a recess 22 in the underside of said base.

In practice, the mat or base 1 is placed upon 60 the floor, and the player swings his golf club to strike the head 11 of the target 10. The head 11 bends forward and then uprights itself due to its resiliency ready for the next stroke. The mat or base protects the floor 65 from damage from misdirected strokes and holds the target in a set position against bodily movement.

It is thought that the construction and advantages of this device for practicing golf 70 strokes will be understood and appreciated without further explanation, and it will be understood that slight changes in the details of construction may be made within the scope of the claims.

Having fully described my invention, what 75 I claim is:

1. In a device for practicing golf strokes, the combination of a base, the base having an upper and a lower side, the center of the base being raised at its upper side, the raised portion of the base being of a diamond shape and having forward and rear points, strips extending longitudinally upon the upper side of the base, the raised diamond portion of the 80 base being provided with a transversely extending slot, the base having recesses in its lower side extending from said slot in opposite directions and lateral of each other, a target of resilient rubber, the target having 85 90 95 100

a neck, the neck extending through said slot, the free end of the neck being split in halves, strips of tin embedded in said halves, and said halves being bent in opposite directions and forced into said recesses for holding said target in position.

2. In a device for practicing golf strokes, the combination of a base, the base having an upper and a lower side, the base being provided with a slot extending from its upper to its lower side, the base having recesses in its lower side extending from said slot in opposite directions and lateral of each other, a target, the target having a neck, said neck passing through said slot, said neck being split longitudinally leaving halves, and the free ends of said halves being bent in opposite directions and forced into said recesses for fixing said neck to said base.

20 In testimony whereof I affix my signature.
LAWRENCE E. YAGGI.
